SAFETY RAZOR BLADE DISPENSING MAGAZINE WITH ATTACHABLE USED BLADE RECEIVER

Leopold K. Kuhnl, Stratford, Conn., assignor to Ever-sharp, Inc., Milford, Conn., a corporation of Delaware

Continuation of application Ser. No. 244,029, Dec. 12, 1962. This application July 23, 1965, Ser. No. 477,638
15 Claims. (Cl. 221—102)

The present invention is concerned with the disposal of used safety razor blades after the blades have been ejected from the head of a safety razor by the insertion of a new blade into the head from a blade dispensing magazine. This application is a continuation-in-part of application Serial No. 797,980, filed March 9, 1959, abandoned as of December 21, 1962, and a continuation of my copending application, Serial No. 244,029, filed December 12, 1962.

The object of the invention is to provide a new and improved used blade receiver which is adapted to be attached to the blade dispensing magazine in a novel manner.

While the foregoing statements are indicative in a general way of the nature of the invention other more specific objects and advantages will be apparent to those skilled in the art upon a full understanding of the construction, arrangement and function of the several parts which have been combined to form the magazine and attachable used blade receiver.

Two embodiments of the invention are presented herein but it will, of course, be appreciated that the invention is susceptible of incorporation in other forms coming equally within the scope of the appended claims.

In the accompanying drawings:

FIG. 1 is a side view of the blade dispensing magazine equipped with the new used blade receiver;

FIG. 2 is a plan view of the assembly shown in FIG. 1; FIG. 3 is a bottom view of the assembly;

FIG. 4 is an opposite side view of the assembly;

FIG. 5 is a front end view of the assembly;

FIG. 6 is a rear end view of the assembly;

FIG. 7 is a side view of the blade dispensing magazine before the used blade receiver has been attached to the same;

FIG. 8 is a side view of the used blade receiver before being attached to the magazine;

FIG. 9 is a top view of the receiver;

FIG. 10 is a front end view of the receiver;

FIG. 11 is a rear end view of the receiver;

FIG. 12 is a plan view of the backstop which locks within the rear end of the razor blade dispensing magazine for holding the stack of razor blades in place;

FIG. 13 is a front end view of the backstop;

FIG. 14 is a side view of the backstop;

FIG. 15 is a side view of the same blade dispensing magazine, showing the magazine equipped with a modified form of the new used blade dispenser;

FIG. 16 is a plan view of the assembly shown in FIG. 15;

FIG. 17 is a rear end view of the assembly shown in FIG. 15;

FIG. 18 is a side view of the used blade receiver shown in FIG. 15, before being attached to the magazine; and

FIG. 19 is a top view of the receiver shown in FIG. 15.

Referring first to the embodiment shown in FIGS. 1 to 14, inclusive, it will be observed that the new used blade receiver 10 is adapted to be attached to a blade dispensing magazine 11 of the type commonly used in inserting new blades into the head of an associated safety razor.

Razors of the type with which the magazine 11 is adapted to be used are shown for example in Rodrigues Patent No. 1,969,945, or Preis and Kuhnl application for

2

patent Serial No. 425,618, now Patent No. 2,911,714, dated November 10, 1959, or Kuhnl application for patent Serial No. 734,653, now Patent No. 2,911,713, dated November 10, 1959.

5 The magazine 11, which contains a stack of 12 of new blades 13, is horizontally elongated and is of generally rectangular cross section. It is characterized by a top wall 14 against the underside of which the uppermost blade 13 in the stack of blades is positioned, a bottom wall 15, a near side wall 16, a far side wall 17, and a front end wall 18. The rear end of the magazine 11 is open.

The magazine 11 is provided, at the front end of the far side wall 17, with a forwardly projecting key-like finger 19. The finger 19, when the magazine 11 is to be used to insert a new blade into the head of an associated razor (not shown), is forced endwise into an opening in the resiliently expansible head of the razor, into a position between the cap and seat portions of the head, where small cams 20 and 21 on the finger 19 act to wedge apart the cap and seat portions of the head to both release the clamping pressure on the used blade in the head and facilitate the insertion of the new blade.

The top wall 14 of the magazine 11 is provided with a longitudinally extending open ended slot 22 in and along 25 which a blade pushing member 23 is adapted to reciprocate. The member 23 is generally U-shaped in cross section and is provided exteriorly of the magazine 11 with a finger grip comprising a portion 24 which is positioned against the top wall 14 of the magazine and side portions 25 and 26 which extend alongside the upper portions of the near and far side walls 16 and 17 of the magazine, the side portions 25 and 26 being spaced slightly from the near and far side walls 16 and 17 for a reason which will be explained hereinafter. The blade pushing member 30 35 23 is provided interiorly of the magazine 11 with a thin flat plate portion 27 for endwise abutment with the rear end of the uppermost blade 13 in the magazine. The stroke of the member 23 is limited by small outwardly pressed projections 28 and 29 on the far side wall 17 adjacent the front and rear ends of the latter, which projections are engaged by a small downwardly extending portion 30 40 associated with the side portion 26 of the blade pushing member 23 when the member 23 reaches its fully advanced and fully retracted positions.

The stack 12 of new blades 13 is positioned above the bottom wall 15 of the magazine 11 on an interposed leaf spring 31, which spring acts to press the blades upwardly against the top wall 14 of the magazine. A generally rectangular notch 32 is provided in the upper edge of the far wall 17 of the magazine whereby to permit visual inspection of the number of new blades 13 remaining in the magazine.

The magazine 11 may be advantageously constructed as a one-piece sheet metal stamping with the front end wall 18 formed by flanging the front end of the near side wall 16 toward the far side wall 17, and with the longitudinally extending slot 22 in the top wall 14 formed by spacing apart the confronting edges 33 and 34 of the stamping, but it will of course be appreciated that the magazine 11 may be made in other ways and also of other materials. The front end wall 18 of the magazine is provided with an angularly disposed portion 35 where it joins the front end of the near side wall 16, which angularly disposed portion interfits with the front beveled corners of the sharp edges 36 of the blades 13 and positions all of the blades in the stack 12 against the far side wall 17 in spaced relation to the near side wall 16.

Associated with the rear end of the magazine 11 is a separate sheet metal backstop 37. The backstop 37 is of generally U-shaped rearwardly opening form and is characterized by two laterally spaced slightly diverging side flanges 38 and 39 and a front cross web 40, the latter

position in the head of an associated razor, a separate elongated generally rectangular used blade receiver of open-top box-like formation in telescopic association with the magazine, the bottom wall of the receiver being spaced a substantial distance below the bottom wall of the magazine whereby to provide a compartment for the reception of used blades, the upper portions of the side and end walls of the receiver embracing the side walls and ends of the magazine with the upper edges of the receiver being substantially flush with the upper edge of the magazine, the bottom wall of said receiver being provided with an opening through which used blades are adapted to be inserted into said compartment, and means securing the receiver to the magazine comprising struck-in vertically spaced tangs on opposite walls of the receiver disposed in interlocking engagement with opposite edges of the bottom wall of the magazine.

2. In combination with an elongated generally rectangular blade dispensing magazine having top, bottom and side walls and being adapted to receive a stack of new blades disposed therein with the uppermost blade in the stack being adapted to be pushed endwise into shaving position in the head of an associated razor, a separate elongated generally rectangular used blade receiver of open-top box-like formation in telescopic association with the magazine, the bottom wall of the receiver being spaced a substantial distance below the bottom wall of the magazine whereby to provide a compartment for the reception of used blades, the upper portions of the side and end walls of the receiver embracing the side walls and ends of the magazine with the upper edges of the receiver being substantially flush with the upper edge of the magazine, the bottom wall of said receiver being provided with an opening through which used blades are adapted to be inserted into said compartment, and means for securing the receiver to the magazine comprising a pair of struck-in vertically spaced tangs formed on each end wall of the receiver and disposed in interlocking engagement with the front and rear edges of the bottom wall of the magazine.

3. In combination with an elongated generally rectangular blade dispensing magazine having top, bottom and side walls and being adapted to receive a stack of new blades disposed therein with the uppermost blade in the stack being adapted to be pushed endwise into shaving position in the head of an associated razor, a separate elongated generally rectangular used blade receiver of open-top box-like formation in telescopic association with the magazine, the bottom wall of the receiver being spaced a substantial distance below the bottom wall of the magazine whereby to provide a compartment for the reception of used blades, the upper portions of the side and end walls of the receiver embracing the side walls and ends of the magazine with the upper edges of the receiver being substantially flush with the upper edge of the magazine, the bottom wall of said receiver being provided with an opening through which used blades are adapted to be inserted into said compartment, and means securing the receiver to the magazine comprising a pair of struck-in vertically spaced tangs formed on each end wall of the receiver and disposed in interlocking engagement with the front and rear edges of the bottom wall of the magazine, one tang of each pair extending downwardly into engagement with the upper surface of the bottom wall of the magazine at the front and rear edges thereof and the other tang of each pair extending upwardly into engagement with the lower surface of the bottom wall of the magazine at the front and rear edges thereof.

4. In combination with a blade dispensing magazine having top, bottom and side walls and a stack of new blades disposed therein with the uppermost blade in the stack being adapted to be pushed endwise into shaving position in the head of an associated razor, a separate used blade receiver having side walls, end walls and a bottom wall telescopically fitted over the magazine from the bottom thereof with the upper edges of the side and

end walls of the receiver substantially flush with the upper surface of the magazine, said side and end walls of said receiver being substantially greater in height than the side walls of the magazine whereby the bottom wall of the receiver is spaced substantially below the bottom wall of the magazine so as to provide a compartment for the reception of used blades, the bottom wall of the receiver being provided with an opening through which used blades are adapted to be inserted into said compartment, and struck-in vertically disposed tangs on opposite walls of the receiver in interlocking engagement with the upper and lower surfaces of opposite edges of the bottom wall of the magazine whereby to secure the receiver to the magazine.

5. In combination with a blade dispensing magazine having top, bottom and side walls and a stack of new blades disposed therein with the uppermost blade in the stack being adapted to be pushed endwise into shaving position in the head of an associated razor, a separate used blade receiver having side walls, end walls and a bottom wall telescopically fitted over the magazine from the bottom thereof with the upper edges of the side and end walls of the receiver substantially flush with the upper surface of the magazine, said side and end walls of said receiver being substantially greater in height than the side walls of the magazine whereby the bottom wall of the receiver is spaced substantially below the bottom wall of the magazine so as to provide a compartment for the reception of used blades, the bottom wall of the receiver being provided with an opening through which used blades are adapted to be inserted into said compartment, a struck-in upwardly extending tang on each end wall of the receiver in abutting engagement with the lower surface of the bottom wall of the magazine at the front and rear edges thereof whereby to position the upper edges of the side and end walls of the receiver substantially flush with the upper surface of the magazine, and a struck-in downwardly extending tang on each end wall of the receiver in abutting engagement with the upper surface of the bottom wall of the magazine at the front and rear edges thereof whereby to secure the receiver to the magazine.

6. In combination with an elongated generally rectangular blade dispensing magazine having top, bottom and side walls and being adapted to have a stack of new blades disposed therein with the uppermost blade in the stack being adapted to be pushed endwise into shaving position in the head of an associated razor, a separate elongated generally rectangular used blade receiver of open-top box-like formation in telescopic association with the magazine, the bottom wall of the receiver being spaced a substantial distance below the bottom wall of the magazine whereby to provide a compartment for the reception of used blades, the upper portions of the side and end walls of the receiver embracing the side walls and ends of the magazine with the end walls extending vertically past the front and rear edges of the bottom wall of the magazine, the bottom wall of said receiver being provided with an opening through which used blades are adapted to be inserted into said compartment, and vertically spaced means on the end walls of the receiver directed inwardly thereof into interlocking engagement with the upper and lower surfaces of the bottom wall of the magazine at the front and rear edges thereof for securing the receiver to the magazine.

7. In combination with a blade dispensing magazine having top, bottom and side walls and being adapted to have a stack of new blades disposed therein with the uppermost blade in the stack being adapted to be pushed endwise into shaving position in the head of an associated razor, a separate used blade receiver having side walls, end walls and a bottom wall telescopically fitted over the magazine from the bottom thereof with said end walls extending vertically past the front and rear edges of the bottom wall of the magazine, said side and end

ment, the upper portions of the side walls of the receiver being substantially coextensive with the side walls of the magazine, in closely conforming engagement with the latter, and means for positioning and securing the used blade receiver with respect to the new blade magazine, said means including longitudinally spaced inturned tabs on the receiver, which tabs abut upwardly against the underside of the bottom wall of the magazine, and one or more apertures in the upper portion of one of the side walls of the receiver, which apertures receive and interlock vertically with the outwardly projecting studs on the side wall of the magazine.

13. The combination with an elongated generally rectangular new blade dispensing magazine, which magazine is adapted to hold a stack of new blades, is provided with means for access to the uppermost blade in the stack to push the same endwise out of the magazine into shaving position in the head of an associated razor, and is provided with at least one stud which projects outwardly therefrom; of a structurally separate elongated generally rectangular used blade receiver of open-top box-like formation having bottom, side and end walls, said magazine being telescoped into the upper portion of said blade receiver, with the bottom wall of the receiver spaced from the magazine to provide a compartment for the reception of used blades, one wall of said receiver being provided with an opening through which used blades are adapted to be inserted into said compartment, the upper portions of the side walls of the receiver substantially over-lapping side portions of the magazine and having at least a portion thereof in closely conforming engagement with the latter, and means for positioning and securing the used blade receiver with respect to the new blade magazine, said means including at least one tab on the receiver adapted to engage said magazine thereby to prevent substantial relative movement therebetween and at least one aperture in the upper portion of one of said walls of the receiver, said aperture receiving and interlocking with said outwardly projecting stud on said magazine to preclude substantial relative movement therebetween.

14. In combination with a new blade dispensing means having a magazine adapted to hold and dispense new blades, and a used blade receiving means attached to said new blade dispensing means, said used blade receiving means being of box-like form having a plurality of walls including side, end and bottom walls, and an open top which is closed off by telescoping said magazine therein whereby said side and end walls of said used blade receiving means embrace at least a portion of said magazine, means for positioning said magazine in spaced relation relative to the bottom wall of said used blade receiving means thereby to form a used blade receiving compartment, said positioning means including a deformed portion on one wall of said used blade receiving means adapted for engagement with said magazine, at least one lug means formed on said new blade dispensing means, said lug means projecting through at least one aperture formed in one of said walls of said used blade receiving means to assist in attaching said used blade receiving means to said new blade dispensing means, and an opening in one of said walls of said used blade receiving means communicating with said used blade compartment to permit used blades to be inserted therein.

15. The combination of claim 14 wherein said used blade receiving means is formed of sheet material which is relatively thin to permit folding thereof for placement around said magazine.
